J. A. HAMBERG,
TRAFFIC SIGNAL,
APPLICATION FILED JULY 12, 1921.

1,430,901.

Patented Oct. 3, 1922.

UNITED STATES PATENT OFFICE.

JOHN A. HAMBERG, OF SPRINGFIELD, MASSACHUSETTS.

TRAFFIC SIGNAL.

Application filed July 12, 1921. Serial No. 484,050.

To all whom it may concern:

Be it known that I, JOHN A. HAMBERG, a citizen of the United States of America, and a resident of Springfield, in the county 5 of Hampden and State of Massachusetts, have invented a new and useful Traffic Signal, of which the following is a specification.

My invention relates to improvements in 10 devices designed to be located in main thoroughfares, usually at the intersection of streets, for the purpose of being manually operated to direct traffic, and consists generally of a standard and an upright mov- 15 ably connected with said standard, means to limit such movement, a peculiarly constructed head mounted on said upright and provided with direction-indicating elements, and operating means for certain of said ele- 20 ments, together with such other parts and members as may be necessary or desirable in order to render the device complete and serviceable in every respect, all as herein- after set forth.

25 The primary object of my invention is to produce a comparatively simple and inexpensive, compact, and easily operated traffic signal, with which the operator, by hand manipulation, is able to set the signal quick- 30 ly to indicate the direction or directions to be taken by vehicles and pedestrians, and to make the necessary and almost constantly occurring changes.

Another object is to provide a device of 35 this character with controlling means which can be so readily operated or manipulated that very little skill is involved in such operation, and the amount of attention required therefor is not sufficient to prevent the operator from giving all the attention necessary 40 to his surroundings, irrespective of the signal.

A further object is to construct the device of few parts, and in such a manner that it 45 will not be seriously or even materially affected by the elements.

Other objects and advantages will appear in the course of the following description.

I attain the objects and secure the ad- 50 vantages of my invention, by the means illus- trated in the accompanying drawings, in which—

Figure 1 is a side elevation of a traffic signal which embodies a practical form of 55 my invention, and wherein both stop arms

are extended, portions of the supporting members being broken out near the bottom; Fig. 2, a side elevation of said signal, without the lower portion, wherein one of said arms is in its vertical position, a portion of 60 the other of said arms being broken out; Fig. 3, an enlarged side elevation of the block or head which carries said arms; Fig. 4, an enlarged, central vertical section through said head; Fig. 5, an enlarged bot- 65 tom plan of said head; Fig. 6, an enlarged top plan, with a portion broken away, of the collar which serves as a supporting and limiting or stop member for the rotatable elements; Fig. 7, an enlarged bottom plan 70 of said collar; Fig. 8, an enlarged top plan of the collar at the top of the supporting sleeve; Fig. 9, a side elevation, with the ex- ception of the lower portion, of the signal as illustrated in the first view, but here the 75 rotatably adjustable elements are at right- angles to the position which they occupy in said first view, and, Fig. 10, a sectional de- tail of one of the adjustable connections for operating the arms, this view being on a 80 larger scale than are the other enlarged views.

Similar reference characters designate similar parts throughout the several views.

The main supporting element or standard 85 of this signal preferably consists of a fairly heavy base 1, and an integral sleeve 2 rising from the center of said base. Secured by any suitable means to the top of the sleeve 2 is a fixed collar 3, which collar is cut away 90 on top at 4 to provide two stops 5. Mounted to rotate in the sleeve 2 is an upright in the form of a vertical rod 6. The rod 6 is the element of the signal whereby is had rotary adjustment on a vertical axis. 95

Ordinarily the rod 6 rests at the bottom on the bottom of the passage in the sleeve 2, which passage may extend into the base 1, but provision is made for supporting said rod at a higher elevation should occasion re- 100 quire, as will presently appear. Such pro- vision may be dispensed with.

A collar 7 is mounted on the rod 6 above the collar 3, and secured to said rod by means of a thumb-screw 8 that is tapped into and 105 through said first-named collar and adapted to engage said rod. The collar 7 has a downwardly-extending lug 9, and laterally- extending, oppositely-disposed lugs 10—10. When the parts are assembled, the collar 7 110

bears on the top of the collar 3, and the lug 9 is received in the opening 4 in said last-named collar. It is clear, therefore, that, when the collar 7 is rotated, the movement thereof is limited by the lug 9 which comes into contact with one or the other of the stops 5, according to the direction of such rotation, because said stops are in the path of said lug. The parts and members are so proportioned that one-fourth of a revolution is permitted the collar 7 and the rod 6 with the parts and members carried thereby, that is, a quarter-turn in one direction from one of the stops 5, and a quarter-turn in the other direction from the other of said stops.

The lugs 10 are preferably both on one side of a vertical plane passing through the axial center of the collar 7, so as to make possible the use of a shorter pair of operating levers 11 than would otherwise be possible. If the axis common to the lugs 10 intersected the axial center of the collar 7, the levers 11 would necessarily have to be longer, as will presently be made clear. Each lever 11 is pivotally connected, intermediate of its ends at 12, to the outer end of one of the lugs 10, and such lever is provided at one terminal with a handle 13. Pivotally connected with the terminal of each lever 11 that is opposite to the terminal to which its handle 13 is attached is the lower terminal of a rod 14.

A head 15 is mounted on the top of the rod 6, and a collar 16 is secured to said rod, by any suitable means as a set-screw 17, at a point between said head and the collar 7. The collar 16 is provided with oppositely-disposed, horizontal lugs 18 with the outer terminal of which are pivotally connected, at 19—19, a pair of levers 20. In the present construction each pivot 19 is nearer one end than the other of its lever 20. When both of the levers 20 are disposed in one of their extreme positions they cross each other, and the shorter arms thereof are below and the longer arms thereof above the horizontal plane of the pivots 19, as shown in Fig. 1; when both of said levers are disposed in the other of their extreme positions they are horizontal and in parallel relation with each other, with the shorter arm of each adjacent to the longer arm of the other; and when one of said levers is in one of the extreme positions and the other of said levers in the other extreme position they are relatively disposed, either as illustrated in Fig. 2, or with the relative positions of said levers interchanged.

The shorter arms of the levers 20 are operatively connected with the levers 11, at the terminals opposite to those to which the handles 13 are attached, and the connecting mediums might consist merely of the rods 14. In order, however, that complete and adequate provision be made for the vertical

adjustment of the rod 6, the connections in question are adjustable, and in the present example comprise in addition to said rods 14 a pair of tubular members or sleeves 21. Each rod 14 is received in one of the sleeves 21, and the upper terminal of such sleeve is pivotally connected at 22 with the shorter arm of one of the levers 20. The sleeves 21 may be reenforced at their lower terminals, and they are provided with thumb-screws 23 which are tapped into and through said sleeves to engage the rods 14.

Upon grasping either handle 13 and rocking its lever 11 to elevate the end thereof with which one of the rods 14 is pivotally connected, as at 24, said rod and with it the connected sleeve 21 is elevated, and the lever 20 with which said sleeve is connected is rocked into a horizontal position. And upon grasping either of such handles and rocking its lever to depress the end thereof with which one of the rods 14 is pivotally connected, said rod and with it the connected sleeve 21 is carried downwardly, and the lever 20 with which said sleeve is connected is rocked into an oblique position.

In the event it is desired, in the present construction, to raise the rod 6, so as to locate the head 15 and members supported and carried by said head at a higher elevation, it is simply necessary to loosen the thumbscrews 8 and 23, raise said rod in the sleeve 2 as far as may be desired, relocate the collar 7 in proper relation to the collar 3, provided said first-named collar has been carried up with said rod, and retighten said thumb-screw 8, and also retighten said thumbscrews 23, care first being taken to preserve the former relative position between the levers 11 and 20. When the rod 6 is elevated it carries with it the collar 16 and the levers 20, and causes the sleeves 21 to be drawn upwardly on the rods 14. In this manner the connections between the levers 11 and 20 are lengthened. Such connections may be shortened in a generally similar manner in the event the rod 6 be lowered, as will readily be understood. Vertical adjustment of the rod 6 in no way affects the operation of the device, which operation will subsequently be explained in full.

The head 15 is preferably a hollow cube having delineated on two oppositely-disposed sides thereof the word Go, and pivotally connected with the other oppositely-disposed sides thereof two stop arms 25 in the shape of arrows. The word Stop is delineated on what may be termed the front side of each arm 25. The head 15 is rigidly attached to the top of the rod 6, and a lantern 26 is mounted on and rigidly attached to the top of said head. The lantern 26 may have four light openings therein with glasses or lenses of different colors in such openings, as, for example, green glasses or

lenses in the openings which correspond with the sides of the head 15 on which the word Go is delineated, and red glasses or lenses in the openings which are on the same sides with the arms 25.

The inner or upper terminal of each arm 25, according to the position of said arm, is rectangular, of a size to correspond with the side of the head 15 against which such part is located, and mounted on a hub 27 that extends horizontally from one side or the other of a horizontal crosspiece 28 in said head. A rod 29 has its lower terminal connected at 30 with the longer arm of one of the levers 20, and its upper terminal connected at 31 with one of the arms 25. The rods 29 pass upwardly through and operate in slots 32-32 in the bottom of the head 15, and connect from the inside of said head 20 with the arms 25. The part of each arm 25 which is mounted on one of the hubs 27, and with which one of the rods 29 is connected, is designated by the numeral 33, and the point of connection (31) between such rod 25 and such part is so located as to enable the arm operated by said rod to be rocked on its hub 27 into a horizontal or a vertical position. In order to fix the limits of movement of each arm 25, so that said arm shall be 30 stopped when it reaches either a horizontal or vertical position, according to the direction of movement, a generally annular opening is formed in the head 15 around the outer terminal portion of each hub 27, 35 and the edge of such opening is shaped to produce a pair of stops 34 and a pair of stops 35. Thus there are four of such stops in each of the perforated sides of the head 15, so that the arms 25 and the operating 40 mechanism therefor can be used interchangeably, although only two of the stops are employed on a side, and those employed on one side are diametrically opposite to those employed on the other side. When the mechanism 45 is operated to throw either arm 25 into a horizontal position, the upper bent terminal of the rod 29 that is connected with and directly operates such arm encounters its stop 34 at the instant said arm arrives 50 in said position, and so prevents further movement in the same direction, and retains or assists in retaining the arm in said position. In Fig. 3 the position of the bent head of one of the rods 29 relative to the 55 stop 34 with which said head is in engagement, when the attached arm is positioned horizontally, is indicated by dotted lines 36; and the position of said bent head relative to the stop 35 with which said head is 60 in engagement, when the attached arm is positioned vertically, is indicated by dotted lines 37.

The arms 25 are held in place on the hubs 27 by means of screws 38-38, and the required tension for said arms is obtained by

means of two springs 39. Each screw 38 is tapped into the outer end of one of the hubs 27, and washers 40 and 41 are interposed, respectively, between the head of said screw and the contiguous part of the arm 25 which is held in place by said screw, and between said part and one of the springs 39. Each spring 39 is introduced between a shoulder 42 at the inner end of one of the hubs 27 and the washer 41 mounted on said hub. Thus 75 it is seen that the springs 39 bear against the washers 41 and force them with the parts 33 of the arms 25 outwardly against the washers 40 and the heads of the screws 38, so that said parts are always subjected to a 80 certain amount of frictional resistance, which amount is sufficient to retain said arms in whatever position they may be located. The washers 40 are generally made of fiber and the washers 41 of metal. 85

The rod 6 with all attached and supported parts above the collar 3 can be rotated, within the limits fixed by the stops 5, upon grasping either of the handles 13 and actuating such handle in the required direction, and 90 either arm 25 can be swung into either a horizontal or vertical position by grasping the handle 13 of the lever 11, which operates said arm through the medium of the intervening connecting members 14 and 21, lever 95 20, and rod 29, and rocking said lever 11 on its pivot 12. If both handles 13 be grasped and actuated to rock both levers 11, the two arms 25 are actuated or operated simultaneously. 100

When the arms 25 are disposed as shown in Fig. 1, the signal is set to stop the traffic in both directions which are at right-angles to said arms, and to open the traffic in the directions parallel with said arms. 105

When it is desired, as is the case where one street intersects another without continuing beyond the same, to signal for the stopping of the traffic on one side and to leave it open on the other side of the main 110 thoroughfare, the arms 25 are disposed as shown in Fig. 2, wherein one of said arms is positioned horizontally and the other vertically. The relative positions of the arms in this case are interchanged when the conditions require that the left-hand instead of the right-hand arm be disposed horizontally and the other vertically. 115

Upon giving the rod 6 a quarter turn to carry the lug 9 from the rear stop 5 into contact with the forward stop 5, assuming that the signal as it stands in the first view be in front of the operator, the parts and members carried and supported by the rod 6 are disposed as shown in Fig. 9, and the signal 120 125 is set to open the traffic in the directions previously closed by the arms 25, and to close the traffic in the directions at right-angles thereto.

From the foregoing it is plain that this 130

signal affords ample means for controlling traffic in practically any place where the same may be employed, and this with the utmost ease and facility.

5. The levers 20 are made with long and short arms for the purpose of reducing the amount of movement required of the levers 11 to operate the arms 25.

The openings in the sides of the head 15, 10 through which the hubs 27 extend, are closed at all times by the parts 33, so that dust and rain and snow are excluded, and the construction of the signal as a whole is of such a nature that it is not seriously affected by 15 the elements.

The lateral arcs 43 between the stops 34 and 35 mark the paths described by the bent parts or heads of the rods 29 in their movement in raising and lowering the stop or indicator arms 25, and may serve as guides for said heads, that is to say, two of such arcs may so serve, it being remembered that said rods extend into the head 15 from below and then turn outwardly to engage or be engaged 25 with the parts 33—see Fig. 3.

More or less change in the shape, size, construction, and arrangement of some or all of the parts of this signal, in addition to those hereinbefore specifically pointed out, 30 may be made without departing from the spirit of my invention or exceeding the scope of what is claimed.

I am aware that devices or appliances employed for traffic signal purposes have been 35 provided with rotatable and oscillatory elements, and do not, therefore, seek to claim broadly such a device or appliance.

What I do claim as my invention, and desire to secure by Letters Patent, is—

40 1. The combination, in a traffic signal, with a standard, of an upright rotatably supported by said standard and provided with a head, indicator arms pivotally connected with said head, and arranged and 45 adapted to be extended in opposite directions beyond two opposite sides thereof, and means for rotating said upright and actuating said arms independently into and out of an approximately horizontal position.

50 2. The combination, in a traffic signal, with a standard, of an upright rotatably supported by said standard and provided with a head, said head having fixed indicator devices on two of its opposite sides, indicator 55 arms pivotally connected with the other two opposite sides of said head, and means to rotate said upright and actuate said arms independently into and out of an approximately horizontal position.

60 3. The combination, in a traffic signal, with a standard, of an upright rotatably supported by said standard and provided with a head, indicator arms pivotally connected with said head, and means, consisting 65 in part of a pair of levers, for rotating said

upright and actuating said arms independently into and out of an approximately horizontal position.

4. The combination, in a traffic signal, with a standard, of an upright rotatably 70 supported by said standard and provided with a head, indicator arms pivotally connected with said head, means to actuate said arms independently into and out of an approximately horizontal position, and means 75 to adjust said upright vertically.

5. The combination, in a traffic signal, with a base and sleeve, said sleeve being provided with stops, of a rod rotatable in said sleeve and provided with a head, a collar 80 secured to said rod and having a stop member to cooperate with said stops, operating levers pivotally connected with said collar, indicator arms pivotally connected with said head, and operating means between said 85 levers and said arms.

6. The combination, in a traffic signal, with a base and sleeve, of a rod rotatable in said sleeve and provided with a head, a collar adjustable on said rod and adapted to be 90 supported by said sleeve, operating levers pivotally connected with said collar, indicator arms pivotally connected with said head, a second sleeve secured to said rod, levers pivotally connected with said second 95 sleeve, adjustable connections between said first-named and said second-named levers, and connections between said second-named levers and said arms.

7. The combination, in a traffic signal, 100 with a base and sleeve, of a rod rotatable in said sleeve and provided with a head, a collar adjustably secured to said rod and adapted to be supported by said sleeve, operating levers pivotally connected with said collar, 105 indicator arms pivotally connected with said head, a second collar secured to said rod, levers pivotally connected with said second collar, connections between said first-named and said second-named levers, said connections comprising rods connected with one pair of said levers, tubular members in which said rods are receivable connected with the other pair of said levers, and means to bind said rods to said tubular members, 110 and rods between said second-named levers and said arms.

8. The combination, in a traffic signal, with a base and sleeve, and a collar secured to said sleeve and provided with stops, of 115 a rod rotatable in said sleeve and having a head, a collar secured to said rod and provided with a lug to operate between said stops and limit the rotary motion of said rod, said second-named collar being receivable on said first-named collar, operating levers pivotally connected with said second-named collar, indicator arms pivotally connected with said head, and operating mechanism between said levers and said arms. 120 125 130

9. The combination, in a traffic signal, with a standard, of an upright rotatably supported by said standard, and provided with operating levers, a head, and an intermediate collar, levers pivotally connected with said collar in such a manner that they are unequally divided by their pivots, connections between said first-named levers and the short arms of said second-named levers, 5 indicator arms pivotally connected with said head, and connections between the long arms of said second-named levers and said indicator arms.
10. The combination, in a traffic signal, 15 with a standard, of an upright carried by said standard and provided with a head, said head having fixed indicator devices on two of its opposite sides, indicator arms pivotally connected in offset relationship laterally 20 with the other two opposite sides of said head, said fixed indicator devices being between the parallel planes of said arms, and mechanism adapted to operate said arms either singly or both together.
11. The combination, in a traffic signal, 25 with a standard, of an upright carried by said standard, a head mounted on said upright and provided with hubs and stops, indicator arms mounted on said hubs, and operating mechanism for said arms, said mechanism consisting in part of rods which have bent parts to engage said arms, and said stops being in the paths of said bent parts.
12. The combination, in a traffic signal, 30 with a standard, of an upright carried by said standard, a head mounted on said upright and provided with hubs, indicator arms mounted on said hubs, resilient means to impart frictional resistance to said arms, 35 and operating means for said arms.
13. The combination, in a traffic signal, with a standard, of an upright carried by said standard, a head mounted on said upright and provided with hubs and stops, indicator arms mounted on said hubs, resilient 45 means to impart frictional resistance to said arms, and operating mechanism for said arms, said mechanism consisting in part of longitudinally movable rods having bent parts to engage said arms, and said stops 50 being in the paths of said bent parts.
14. The combination, in a traffic signal, with a standard, of an upright carried by said standard, a head mounted on said upright and provided with shouldered hubs, 55 indicator arms mounted on said hubs, screws tapped into said hubs with the heads of said screws outside of said arms, springs interposed between said shoulders and said arms, and longitudinally-movable operating members 60 for said arms and connected therewith.
15. The combination, in a traffic signal, with a standard, of an upright carried by said standard, a head mounted on said upright and having openings in two sides 65 thereof, the edges of said openings forming stops, and said head being provided with hubs, indicator arms mounted on said hubs, and operating mechanism for said arms, said mechanism consisting in part of longitudinally-movable rods which extend into said head and have bent parts that extend through said openings to engage said arms, 70 and said stops being in the paths of said bent parts.
